UNITED STATES PATENT OFFICE.

WILLIAM S. HOGG, OF THE UNITED STATES NAVY, ASSIGNOR OF ONE-HALF
TO THE GREATER NEW YORK SECURITY COMPANY, OF NEW YORK, N. Y.,
A CORPORATION OF NEW YORK.

TUNING DEVICE FOR WIRELESS TELEGRAPHY.

SPECIFICATION forming part of Letters Patent No. 719,005, dated January 27, 1903.

Application filed March 4, 1902. Serial No. 96,675. (No model.)

To all whom it may concern:

Be it known that I, WILLIAM S. HOGG, lieutenant-commander, United States Navy, residing at Washington, in the District of Columbia, have invented certain new and useful Improvements in Condensers for Electric Circuits; and I do hereby declare the following to be a full, clear, and exact description of the invention, such as will enable others skilled in the art to which it appertains to make and use the same.

My present invention relates to improvements in wireless telegraphy, being a tuning device used in any wireless-telegraphy circuit or circuits, in which is ordinarily contained a condenser and self-induction coils. The device is used to accomplish tuning by varying the capacity and self-induction of any circuit or circuits, according to the formula

$$T = \frac{2 \pi \sqrt{LC}}{10^3}$$

C, the capacity, and L, the self-induction, being made so large that T, the period of oscillation, is also large, and only like instruments with a like large period will respond sympathetically. To attain this attuning, one or more stations must have like devices in every respect, with indices that throw the relative self-induction and capacity at the same marks on like arbitrary scales, all other parts of the wireless-telegraphy system being exactly similar.

My invention comprises, among other parts, an outer metal spiral surface, preferably fixed, and an inner metal spiral or continuous surface movable axially within the outer surface and separated therefrom by a proper dielectric. The capacity can be varied by moving the inner surface longitudinally within the outer and the self-induction varied by short-circuiting adjacent convolutions of the outer spiral by plugs or a sliding contact. The inner surface can be a spiral, a continuous metal tube or rod, a metal tube containing iron filings, or bundle of iron wires wound with insulated wire.

My invention further comprises the combination and arrangements of parts herein-after more particularly described, claimed, and shown in the accompanying drawings, in which—

Figure 1 represents in central vertical section, with parts in elevation, a form of condenser embodying my invention. Fig. 2 represents a section taken along the line 2 2, Fig. 1, and looking in the direction of the arrow. Fig. 3 represents a portion of the outer spiral in side elevation. Fig. 4 represents a section taken along the line 4 4, Fig. 1, and looking in the direction of the arrow; and Fig. 5 is a diagrammatic view of the working of the apparatus in wireless telegraphy.

Similar letters refer to similar parts throughout the several views.

The device shown in the drawings comprises, among other parts, a metal spiral shell *a*, open at both ends and conveniently formed by taking a drawn brass or other metal tube and marking out on its surface a spiral of a desired pitch—four inches, for example—and then cutting the tube from a point about an inch from one end to the other along the spiral line. This tube *a* is then slipped over a tube *b*, of glass, hard rubber, or other suitable dielectric, which extends at both ends beyond the tube *a*. I may, however, use oil or even air as a dielectric; but glass or hard rubber is preferred. Within this tube *b* is adapted to slide a metal tube *c*, closed at one end and either cut in a spiral, as shown, or continuous. If spiral, the spirals of this tube are preferably of a pitch of one inch—that is, in case the spirals of the outer tube *a* are of a four-inch pitch.

Into the closed end of the tube *c* I tap a rod *d*, which extends beyond the end of the tube *b* and in the case shown is bent at right angles to form an index *d*' for a stationary scale *e*. This rod *d* at the same time forms a support for the end of the inner tube *c* and is for this purpose mounted in a bracket or stand *f*, adapted to slide in a guide or way *g*, and in case this stand is metal the said rod *d* is insulated therefrom, as by the bushing of insulation *h*. The stand *f* may be clamped in the desired position by the set-screw *i*.

The device may be mounted in any suitable insulating-support, such as the support *j*, and these, together with the guide *g* and support *k* for the scale, may be mounted on any suitable base *l*.

The scale *e* is graduated from "34" to "1," corresponding to the convolutions of the in-

ner tube *c*, so that when the said tube is all the way in the outer tube *a* the index will point to "34," and when the said tube is pulled out until only one turn of the spiral is within the outer tube the index will point to "1." The figures on the scale, therefore, indicate the relative capacity.

For the purpose of varying the self-induction of the condenser-circuit I provide the outer spiral tube *a* with a series of plug holes *a'*, one between each pair of adjacent turns of the spiral. By inserting metal plugs in these holes any number of turns of the spiral may be cut out and the self-induction varied accordingly. When none of the outer spiral turns are short-circuited, as above explained, the self-induction of the circuit may be indicated *L*⁸, there being eight turns of said coil. If one plug is inserted and leaves one coil cut out, the self-induction will be relatively *L*⁷, and so on, the self-induction varying with the number of turns cut out. I do not, however, confine my invention to this specific graduation, as any arbitrary figures may be assumed.

25 The device may be provided with any suitable terminals. In the drawings I have represented the terminals *m m'* by wires soldered to the first turn of the outer casing *a* and the last turn, respectively. There are also terminals on the ends of the inner spirals *n* and *n'*.

35 Figs. 1 and 5 show two of the many ways of using the device. In Fig. 5 the combined sending and receiving wire is attached to the terminal *n'*, and *n* is led to ground by the circuit, one of which is through the coherer *v*. In sending the throw-over switch *t* cuts out the circuit through the coherer, and in receiving the circuit is cut out excepting through the coherer. O in all the figures is an inductorium or source of high-tension electricity.

I claim as my invention—

1. A tuning device for electric circuits, hav-

ing a combined variable self-induction and variable capacity.

2. A tuning device consisting of an inner 45 and outer spiral surface, an intervening dielectric, and means for varying the mutual induction of such spiral surfaces by short-circuiting one or more turns of either spiral.

3. In a tuning device for use in wireless 50 telegraphy, the combination with two spiral surfaces or coils, with an intervening dielectric, of combined means for varying the mutual induction between said coils and at the same time varying the capacity of the system, 55 substantially as described.

4. A tuning device, consisting of a spiral metal surface forming one coating of a Leyden jar, a spiral metal surface concentric with the first-mentioned surface and capable of 60 movement relative thereto, forming the other coating, a dielectric separating the two coatings, means for short-circuiting the outer spiral and thus varying the self-induction of a circuit, and indices for indicating the relative 65 amount of such capacity and self-induction.

5. A tuning device, consisting of the following: a spiral metal shell forming one coating of a Leyden jar, a metal shell or rod concentric with the first-mentioned shell, capable of movement relative thereto and forming the other coating, a dielectric separating the two shells, means for short-circuiting one or more turns of the outer spiral and thus varying the self-induction of a circuit, and indices 70 for indicating the relative amount of such capacity and self-induction.

In testimony whereof I affix my signature in presence of two witnesses.

W. S. HOGG.
